1

This invention relates to a lighting dynamo, more particularly for internal combustion engines, adapted for lighting and/or sparking purposes, or similar machines.

Lighting dynamos of this type for internal combustion engines are known in which a system consisting of permanent magnets rotates about one or more coils. The rotatory magnet system was originally constructed in such a way that at first two bar magnets were bent and provided with pole shoes. These magnets were accommodated in a casing of a non-magnetizable material. This design resulted from the fact that the chromium and cobalt steels used in the beginning of the development of these devices had a relatively small coercitive force. When high-quality material for magnets became available, the magnets could be gradually reduced in size and a greater number of magnets could be accommodated on the same circumference. However, a casing of a non-magnetizable material consisting of brass, bronze, aluminum castings or the like continued to be used for the magnets.

This arrangement has the disadvantage that the total weight is relatively high for a given flywheel moment. Another drawback of the said arrangements consists in that owing to the relatively low tearing strength of the alloys used for the casing the danger of an explosion of the aggregate existed if the internal combustion engine by any chance was operating with excessive speed. Such explosions actually did happen in practice. Therefore, the manufacturers were compelled to specify a maximum speed.

Since the rotatory magnetic system with its carrier simultaneously served as a flywheel for the internal combustion engine, it was oftentimes necessary to accommodate the magnetic system with its non-magnetic armoring in an iron casing. In this case, it was necessary, however, to provide a certain distance from the magnet in order that the lines of magnetic force were not deflected.

Finally, the machines also have to be protected against dirt and water; to this end in the previous types a protective cap of a non-magnetizable material had to be provided, whereby the manufacturing costs, of course, were increased.

It is the object of the present invention to provide a design by which all the said disadvantages of the known designs with non-magnetic casing are avoided.

Further objects of the invention will appear as the specification proceeds.

According to the invention a magnetic material

2

closing the outer magnetic circuit between the single magnets is used as a carrier for the magnet. More particularly, iron is used for this purpose. The magnets are radially disposed on their carrier so that contrary to the existing types the lines of magnetic force in the magnet run approximately parallel to the radius passing through the centre of the magnet, while the magnetic flux in the known types followed approximately the direction of the circumference in the bent magnets. A further advantage of the system according to the invention resides in the fact that the magnets can be produced as simple prismatic bodies which engage the carrier and possibly the pole shoes with a relatively large base surface.

The magnets may be either provided with separate pole shoes or their head portion itself may be formed as a pole shoe. In the first case the pole shoes may consist of flat iron while it had been necessary so far to make them of high quality dynamo sheets. The pole shoes may be provided with steps so that the adjustment of the ignition moment is facilitated without requiring any turning of the coil system. The pole shoes or the magnets respectively are advantageously secured to the carrier with the aid of fixing means of a non-magnetic material, e. g., by brass pins, so as to avoid any magnetic connection from the pole shoe or its inner pole surface to the carrier. Owing to its construction from a magnetic material, more particularly iron, the carrier can be drawn in the form of a pot and may consist of an integral piece with the hub, whereby the machining operations and parts so far required for fixing the hub can be dispensed with. It is also possible to weld the hub directly to the casing while this was impossible, for reasons of mechanical strength, with the materials used so far.

Very frequently it is necessary to fit the lighting dynamo into the blower wheel serving for cooling the internal combustion engine. According to the invention the casing or carrier for the permanent magnets may be formed as an iron ring in this case also and accommodated in the blower wheel. By this design the whole expensive construction of the blower wheel of a non-magnetizable material and the additional flywheel masses which had to be spaced by a considerable distance from the magnet can be dispensed with. The use of iron for the blower wheel caused a reduced efficiency in the previous designs unless a larger distance was provided from the edge of the blower to the magnets, with its known disadvantages. Moreover, the magnets may now be

accommodated directly in a blower wheel consisting of iron. The protective cap may be made of sheet iron in the same manner.

Further objects and features will be seen from the following detailed description in connection with the accompanying drawing showing by way of example and purely schematically some embodiments of the invention and in which:

Fig. 1 is an axial section through a lighting machine,

Fig. 2 is a front view of the permanent magnet system of Fig. 1, the coils and the cores thereof being indicated by dotted lines,

Fig. 3 is an axial section through a magnetic system in which the carrier consists of a ring,

Fig. 4 is a front view of a magnet which is inserted in an annular carrier and whose head face is in itself formed as a pole shoe,

Fig. 5 is a partial view same as Fig. 4, showing a stepped pole shoe for the adjustment of different ignition times,

Fig. 6 is a section through a lighting machine with dust cap and fan blades, and

Fig. 7 is a partial view of Fig. 6.

Similar reference numerals denote similar parts in the different views.

Referring now to the drawings in greater detail, it will be seen that the magnets are shown at 1, four such magnets being provided according to Fig. 2.

These magnets, consisting of high quality magnet alloys, e. g. of a nickel, aluminum, iron alloy with small additions of cobalt, chromium or tungsten, or of iron, nickel, cobalt and titanium, are secured with their end face 2 to the rim 3 of a pot-shaped casing 4, e. g. of iron which may be formed integral with the hub 5, a set of coils 6 being provided inside said casing in known manner. The whole system is covered by a cap 7 of magnetic material.

In the embodiment as per Fig. 3, the magnets 1 are built into an annular carrier 8 which is inserted in the casing 9 of magnetizable material.

In the embodiments according to Figs. 1 to 3 pole shoes 10 which according to the invention may consist of flat iron are attached to the inner end faces of the magnets and the magnets are held by means of fixing pins 11 consisting of a non-magnetizable material, e. g., of brass.

As shown in Fig. 4, the pole surface 12 of the magnets 1 can be designed in such a way that additional pole shoes may be dispensed with.

Moreover, as shown in Fig. 5, it is possible to provide the pole shoes with steps 13 in such a way that two breaking edges 14 and 15 are formed which render it possible in known manner to adjust the ignition time without readjusting the coil plate, possibly by means of automatic adjustment of the breaking cam or by readjustment of the break.

In the embodiment as per Figs. 6 and 7 fan blades 16 also consisting of iron or the like and forming the blower wheel serving for cooling the motor are provided on the casing 4. In this case it is possible to use the blower wheel itself as a carrier for the permanent magnet. This figure also shows how the hub 5 is welded into the casing 4 at 17.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described our invention, we claim as new and desire to secure by Letters Patent:

1. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; and at least one coil arranged between said hub and said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier.

2. A magneto-electric machine comprising in combination, a rotatable carrier consisting of magnetic material and having a hub; a plurality of permanent magnets having center lines radially disposed and arranged with the axes thereof in radial directions, respectively, and in symmetrical configuration in said carrier with respect to said hub and with equal distances therefrom, said magnets being in direct contact with said carrier; and at least one coil arranged between said hub and said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier.

3. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; a plurality of iron pole shoes secured to said magnets, respectively, and having part-cylindrical surfaces arranged symmetrically about said hub; and at least one coil arranged between said hub and said pole shoes of said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier.

4. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; a plurality of iron pole shoes secured to said magnets and forming the head portions thereof, respectively, and having part-cylindrical surfaces arranged symmetrically about said hub; and at least one coil arranged between said hub and said pole shoes of said magnets and having a magnetic

core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier.

5. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; a plurality of iron pole shoes secured to said magnets, respectively, and having part-cylindrical surfaces arranged symmetrically about said hub; at least one coil arranged between said hub and said pole shoes of said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier; and steps formed in said part-cylindrical surfaces of said pole shoes, said steps facilitating the change of the magnetic flux in said core when said magnets rotate.

6. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; at least one coil arranged between said hub and said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier; and an end plate arranged on said carrier and forming a flywheel mass associated with said carrier.

7. A magneto-electric machine comprising in combination, a rotatable carrier consisting of

magnetic material and having a hub; a plurality of permanent magnets having center lines radially disposed and arranged in a symmetrical configuration in said carrier with respect to said hub and with equal distances therefrom; at least one coil arranged between said hub and said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier; and an end plate arranged on said carrier and forming a flywheel mass associated with said carrier and including a plurality of fan blades.

8. A magneto-electric machine comprising in combination, a rotatable carrier consisting of magnetic material and having a hub; a plurality of permanent magnets having center lines radially disposed and arranged in a symmetrical configuration in said carrier with respect to said hub and with equal distances therefrom; at least one coil arranged between said hub and said magnets and having a magnetic core arranged with the axis thereof at any moment at right angles to one of the radial directions from said hub to said carrier, whereby the magnetic circuit extends from said magnetic carrier through one of said magnets substantially parallel to the center line thereof, said core of said coil, and another of said magnets substantially parallel to the center line thereof and back to said magnetic carrier; and a protective cap consisting of a drawn sheet metal body and arranged so as to cover said carrier and said magnets.
